MOSES L. COHN, OF BROOKLYN, NEW YORK

BEDSPRING

Application filed April 11, 1929. Serial No. 354,395.

This invention relates to furniture and more particularly to a bed spring.

Many persons object to a double bed as the spring has a tendency to sag in the middle and also due to the fact that large sheets and blankets must be used which are not only hard to handle but are also expensive. Twin beds have been used but many do not find them practical as they require extra room.

20 Therefore, one object of the invention is to provide a spring for use upon a double bed so constructed that separate mattresses may be supported thereon and thereby provide the convenience of individual beds.

25 Another object of the invention is to provide a bed spring including a frame of the proper size to fit a double bed and so constructed that it will be very strong and rigid.

30 Another object of the invention is to provide the spring with mattress supporting units which are entirely separate from each other and spaced from each other transversely of the frame a sufficient distance to allow 25 sheets, blankets and the like to be easily tucked under mattresses supported thereby without interference.

The invention is illustrated in the accompanying drawings, in which:

35 Figure 1 is a top plan view of the improved bed spring.

Figure 2 is a transverse sectional view through the spring taken on the line 2—2 of Figure 1.

35 Figure 3 is a longitudinal sectional view through the spring.

Figure 4 is an end elevation of a modified form of spring.

40 Figure 5 is a perspective view of one of the brackets shown in Figures 2 and 4.

Figure 6 is an end elevation of another modified form of spring.

The improved bed spring includes a frame having side bars 1 and a center bar 2 which 45 extend the full length of the frame and may be either solid or of a tubular construction. Brackets 3 and 4 are carried by the ends of the bars 1 and 2 and each is firmly secured upon the end of the bar to which it is applied.

50 Each of the brackets 4 is provided with a

sleeve 5 which fits tightly upon the bar 2 and arms 6 extending upwardly at an outward incline transversely of the bar and each terminating in a flat head 7. The brackets 3 are formed of strong sheet metal and each has its lower portion formed with an opening 8 to receive the end of the bar 1 to which it is applied and a corner portion removed to form a shoulder 9 and prevent the bracket from slipping when set upon a ledge of a bed rail. The heads 7 of the brackets 4 and the upper ends of the brackets 3 fit flat against the depending flanges 10 of the end bars 11 where they are secured by rivets 12 so that they will be firmly secured to the end bars. If so desired, each end bar may be formed in sections as shown in Figure 4, where the two sections are indicated at 11'. In this figure there has also been shown bearing rods 13 which connect the brackets 3 70 and 4.

The mattress supporting units are of a duplicate construction and each includes end strips 14 connected by side strips 15 thereby defining rectangular frames to which a 75 fabric 16, upon which a mattress is to rest, may be secured. This fabric may be formed of links joined together, as shown in Figure 1, or interwoven wires or the like. Coiled springs 17 connect the end strips 14 with the 80 end bars 11 or 11' and, therefore, the mattress supporting units or elements will be yieldably connected with the end bars of the frame and allowed to have sufficient give to yieldably support a mattress.

When this improved bed spring is in use, it is set in place in the usual manner and the shoulders 9 of the brackets 3 rest upon side rails of a bed. The mattresses rest upon the mattress supporting units and bed covering 90 may be applied in the usual manner and tucked in at the lower ends and along both sides of the mattresses. I have, therefore, provided a spring for use upon a double bed having all of the advantages of separate beds 95 without requiring more space in a room than a double bed of a conventional construction and size.

In Figure 6, there has been shown a modified form of the invention. In this figure, 100

the numerals 18 represent box springs of a conventional construction. These box springs rest upon a suitable number of cross bars 19 spaced from each other longitudinally of the box springs and the cross bars 5 at the ends of the box springs carry depending cleats 20 to bear against side rails of a bed upon which the cross bars rest and prevent transverse shifting.

Having thus described the invention, I 10 claim:

1. A bed spring comprising a frame having side bars, and a center bar extending longitudinally of the frame, end bars disposed in transverse relation to the side bars and center bar and above their ends, brackets carried by the side bars at their ends and extending upwardly therefrom and secured to the end bars, brackets secured tightly about the ends of the center bar and each having arms extending upwardly from opposite sides of the center bar in diverging relation to each other and secured to the adjacent end bar, mattress supporting units extending between said end bars at opposite sides of said center bar, and springs connecting said units with the end bars.
2. A bed spring comprising a frame having side bars, and a center bar extending longitudinally of the frame, end bars disposed in transverse relation to the side bars and the center bar and above their ends, brackets carried by the side bars at their ends and each having its lower portion engaged tightly about a bar and its upper end secured to the adjacent end bar, brackets secured tightly about the ends of the center bar and each having arms extending upwardly from opposite sides of the center bar 35 in diverging relation to each other and secured to the adjacent end bar, rods extending between the brackets of the center bar and side bars and constituting braces, mattress supporting units extending between 40 said end bars at opposite sides of said center bar, and springs connecting said units with the end bars.

In testimony whereof I affix my signature.
MOSES L. COHN. [L. s.]
